ELECTRIC SWITCH

Ben H. Young, Chicago, Ill.

Application March 1, 1939, Serial No. 259,210

2 Claims. (Cl. 200—64)

This invention relates to an electric switch particularly to one adapted to be operated from a remote point and having suitable indicating means to show the position of the switch. A switch of this character finds great utility in blowers or fans and other installations where the motor to be controlled is disposed in an inaccessible location. Such motors as a rule have a plurality of speeds at which they may run so that the control switch must have a plurality of corresponding positions.

It is an object of this invention to devise a switch that will be simple, sturdy, compact and inexpensive.

In general, the switch comprises a pair of spaced superposed insulating discs maintained in suitable relationship to each other by a plurality of rigidly spaced conducting members. These members and the two discs together form a rigid framework inclosing an interior region within which the switch mechanism proper is installed. Each of the spacing members carries a fixed contact which extends inwardly towards the central region. A shaft rotatably mounted in both discs extends through the central region and carries a rotor. This rotor may carry one or more suitable contacts to cooperate with the fixed contacts for switching purposes.

In order to promote easy assembly, each of the spacing members is adapted to be threaded through the contacts and through suitable apertures in both discs. A connecting lug for each spacing member is conveniently provided by having the lug threaded over a portion of the spacing member and forced tightly against one of said insulating discs to maintain the lug in position. Hence, assembly operations are reduced to a minimum.

Any suitable actuating means for the rotor may be provided and in this case the rotor is provided with a ratchet wheel which is operated upon by a spring and pawl assembly extending into said central region from between two spacing members. The pawl itself may be operated by any chain or any other means from a remote point and serves to advance the switch one step at a time. To provide a convenient means for indicating the rotor position, a suitable indicating disc is mounted upon said shaft to turn therewith. Preferably this disk is mounted upon a free portion of the shaft extending beyond one of said discs. The entire switch may be disposed in a suitable housing provided with a window through which a portion of the indicating

disc appears and past which the disc is adapted to move.

Because of the assembly of the switch and the disposition of the lugs, but little difficulty is experienced in disposing the switch in comparatively limited spaces and in making suitable connections therewith.

In order that the invention may be more fully understood it will now be explained in connection with the drawing in which:

Figure 1 is a view of the switch supported in a housing;

Fig. 2 is a detail of the indicating disc;

Fig. 3 is a top view of the switch with parts broken away;

Fig. 4 is a section on line 4—4 of Fig. 3; and
Fig. 5 is a detail of a spacing member.

Referring to Figs. 3 and 4 there is shown an insulating disc 10 of generally circular outline. In spaced relation thereto is a second insulating disc 11 of similar shape maintained by a plurality of spacer members 12 and 12'. Each spacer member is of suitable metal, such as brass, and as shown in Fig. 5 has reduced ends or tenons 13 and 14. These tenons are threaded through suitable registering apertures or mortises in the two discs 10 and 11. As is clearly evident in Fig. 3, the spacer members are disposed along the peripheral edge portions of the discs and form therewith a frame enclosing a central interior region.

The spacer members 12 and 12' each support a stationary contact 17 and 17' by having one of its tenons, here shown as 13, threaded through mortised mounting portion 18. The mounting portion is wedged between the shoulders of spacer 12 and the inside surface of disc 10. The stationary contact members 17 have spring portions 19 bent over to form a generally U-shaped section.

The other tenon 14 of each spacer is threaded through a soldering lug 22 which normally extends outwardly away from the edge of disc 11. The protruding ends of the tenon may be peened over to lock the assembly in position. It will be noted that spacers 12 are uniformly disposed around the peripheries of the discs. One spacer 12' is disposed between two normal spacers 12. This spacer 12' is insulated from casual contact by a strip of fiber 25. The contact member 17' has its free end 19' shaped somewhat differently than the remaining contact ends 19.

Rotatively supported by the two discs 10 and 11 is a stub shaft 28. This shaft normally passes through the centers of the discs and has the

portion 29 between discs enlarged to form a square section. An insulating rotor 30 is carried by shaft portion 29 and normally lies against the inside surface of disc 10. The rotor 30 has an irregular cam shape, as seen in Fig. 3, to provide as many cam projections 31 as there are normal stationary contacts 17. Rotor 30 is made of suitable insulation and has a ground contact 33 at the top and an extension side contact 34. Stationary contact 17 has its free end 19 bearing against ground contact 32. The remaining stationary contacts 17 bear against the sides of the rotor and one of the stationary contacts at a time is adapted to bear against side rotor contact 33. Due to the shape of the rotor and the action of the stationary contacts an index action is obtained.

To indicate the position of the rotor, shaft 28 has a free portion 35 extending beyond disc 11. An indicating disc 36 is mounted on shaft portion 35. Since the switch as shown has five positions, the disc may be marked with the numerals shown or any other indicia. Any other number of switch positions may be provided or a different type of indicator may be used.

The switch rotor is adapted to be advanced one switch position at a time. To accomplish this, shaft portion 29 carries a ratchet wheel 38 having ratchet teeth 39 equal in number to the number of switch positions, here five. A supporting handle portion 40 has a pair of rigid portions 41 and 42 disposed between discs 10 and 11 in a manner similar to spacers 12. Slidably disposed between opposing parallel flat surfaces of portions 41 and 42 is a pawl member 45 having a general U-shape. This member has a pawl arm 46 with a claw 47 to engage a ratchet tooth 39. The other arm 48 is shaped to provide two spring fingers 49 and 50 bearing on shaft portion 29 on opposite sides of ratchet wheel 38. Both arms 46 and 47 are springy and tend to hug the shaft.

To withdraw the pawl member, a flat rod 52 having a head 53 is threaded through an aperture in the base portion of the pawl member 45 and extends into a bore 54 in handle portion 40. A coil spring 55 disposed around rod 52 urges pawl member 45 and rod 52 toward the shaft 28. Rod 52 has its end 56 bent to engage a draw-bar member 57 at a loop portion 58. A suitable chain 60 is engaged by said draw-bar and retained in position by a set screw 61 in a universal lever 62. This lever has an end 63 playing against face 64 of handle portion 40 and may be tilted in any direction to pull out draw-bar 57 against its spring bias. The chain may be used to pull out or tilt universal lever 62 for switch position.

In the position of the switch mechanism as seen in Fig. 3, a pull on the chain will turn the

5 rotor clockwise one switch position. Upon release of the chain, spring 55 urges pawl member 45 toward the shaft. Claw 47 rides around a ratchet tooth toward the front thereof whereupon the spring arms cause the claw to engage a new ratchet tooth in preparation for a new operating cycle.

10 The switch may be conveniently disposed in a housing 65 by clamping between nuts 66 and 67 threaded on the outside of handle portion 40. A window 69 in the housing may be used for exposing an indication on disc 36.

15 For simplicity in manufacturing, it is preferable to so proportion the thickness of disc 11 and lug 22 on one hand and disc 10 and portion 18 of the stationary contacts on the other hand as to be substantially equal. Hence spacers 12 may have equal tenons 13 and 14. By having the soldering lugs and stationary contacts separated by the full length of the spacer body, any heat at the lugs due to soldering will not draw the temper of the contacts.

20 What is claimed is:

25 1. An electric switch comprising a pair of spaced parallel superposed insulating disks having a series of spaced registering mortises therethrough adjacent the edges thereof, a plurality of rigid elongated metal members having both ends of each member formed as similar tenons, said members connecting said disks to form a framework with a central region between said disks, fixed spring contacts for certain members, each contact having a flat mortised mounting portion lying against the inside face of one disk only with a tenon passing through said mortised mounting portion, each contact having a contacting portion extending into said central region, a shaft rotatively mounted in said disk and passing through said central region, a movable contact carried by said shaft and cooperating with said fixed contacts for effecting switching during shaft rotation, means for rotating said shaft for switching purposes, a connecting lug for each contact bearing member, said connecting lug having a flat mortised mounting portion adjacent the other disk only and through which a tenon passes, said lug mounting portion being substantially thicker than the spring contact mounting portion, said one disk being thicker than the other disk to compensate for the difference in thickness between the two metal mounting portions at opposite ends of a member.

30 2. The structure of claim 1 wherein the connecting lugs are disposed against the outer face of said other disk, wherein said shaft extends beyond said other disk and carries an indicating plate spaced from but covering said lug mounting portions.
